AUTOMOBILE-BODY HEATER

Edmund Ludlow, Columbus, Ind., assignor to
Arvin Industries, Inc., a corporation of Indiana

Application April 4, 1949, Serial No. 85,367

2 Claims. (Cl. 257—137)

1

This invention relates to automobile-body heaters and more particularly to automobile-body heaters which deliver heated air both to the interior of the automobile body and to one or more defrosters. It is the object of the invention to simplify the construction, lessen the manufacturing cost, and improve the performance of such a heater.

In carrying out the invention in its preferred form, the heater is provided with a casing having an inlet opening in its bottom. Immediately above this opening there is placed an air-heating core adapted to be connected into the cooling system of the automobile engine whereby air passing upwardly through the core and into the casing will be heated. Within the casing and above the core, I provide an electric motor which drives two air-impelling elements secured to opposite ends of the motor shaft and located respectively adjacent the rear wall and the front wall of the heater casing. One of such air-impelling elements, conveniently the one located adjacent the front wall of the casing, is the impeller of a blower adapted to deliver air to an outlet fitting arranged for connection to one or more conduits extending to a defrosted nozzle or nozzles. The other air-impelling element is arranged to deliver air laterally through air-outlet openings provided in the side walls of the casing near the rear thereof. All air entering the casing passes upwardly through the core and enters the space between the two air-impelling elements, where the air divides into two portions one of which is propelled by the blower to the outlet fitting and the other of which is delivered to the other impeller for discharge through the openings in the side walls of the casing. If desired, the outlet fitting may be provided with a valve and an auxiliary outlet opening, the valve being adjustable to direct air received from the blower either to the defrosters or to the auxiliary opening for discharge directly into the interior of the automobile body.

The accompanying drawings illustrate my invention: Fig. 1 is a vertical section through an automobile-body heater embodying my invention, and is taken substantially on the line 1—1 of Fig. 2; Fig. 2 is a vertical section taken substantially on the line 2—2 of Fig. 1; and Fig. 3 is a vertical section taken on the line 3—3 of Fig. 2.

The heater illustrated in the drawing comprises a casing having side walls 10, a top wall 11, and a rear wall 12. At their lower edges, the side walls 10 are turned inwardly to form flanges providing a support for an air-heating core 13. The front end of the casing is closed by a removable cover 14 having flanges which overlap the side and top walls of the casing 10 as well as the in-turned flanges at the bottom edges of the side walls.

Within the casing 10 there is provided a transverse partition 18 having along its top and sides

walls of the casing 10 and is secured thereto as by screws 20. Attached to the partition 18 is a support 21 for an electric motor 22, such motor being disposed with its shaft 23 normal to the partition 18 and the front cover 14. Co-axially with the motor shaft 23, the partition 18 is provided with a large air-passing opening through which the rear end of the motor shaft 23 extends. In rear of the partition 18 there is secured to the motor shaft an air-impelling element conveniently, although not necessarily, in the form of a fan 25. Between the partition 18 and the rear wall 12 of the casing, the side walls 10 of the casing are provided with openings 26 permitting the escape of air acted upon by the impeller 25. Conveniently, the openings 26 are provided by the inward displacement of louvers 27 which slope outwardly and downwardly to direct air discharged through the openings 26 toward the floor of the automobile body. To improve the efficiency of the impeller 25 its lower portion is partially surrounded by a baffle which extends between the partition 18 and the rear casing-wall 12 and which includes an arcuate portion 28, disposed immediately beneath the impeller 25 and concentric therewith, and outwardly and downwardly sloping end portions 29 which meet the side walls 10 beneath the lowermost opening 26. Below the baffle 28—29, the partition 18 is cut away so as to permit air entering the casing through the core 13 to flow upwardly on the front side of the partition 18.

On the front end of the motor shaft 23 there is secured the impeller 31 of a blower, such blower being disposed within the customary scroll housing 32. The scroll housing is conveniently formed from a pair of opposed sheet-metal stampings having abutting flanges removably secured together as by screws 33. To support the housing 32 in proper position within the casing 10, I may employ posts 35 which are secured to and extend forwardly from the partition 18 to abut at their front ends against ears 36 provided on the rear housing-stamping. Screws 37 extending through the ears 36 and into the posts 35 secure the blower-housing 32 in position.

The blower-impeller 31 is conveniently in the form of a cup-shaped sheet-metal stamping opening rearwardly and provided around its periphery with a series of radially inclined blades 40. The rear wall of the blower-housing 32 has a central opening through which air can enter the impeller 31 so that as the impeller rotates the blades thereon will force such air outwardly into the housing 32 for delivery therefrom into an upwardly directed neck 42 with which the housing is provided.

The upper portion of the casing-cover 14 is provided with an opening for the reception of the discharge-neck 42 of the blower housing, and over that opening there is disposed an outlet-fitting 43. The outlet-fitting 43 has an open bottom to fit against the top wall 11 of the

heater-casing and cover the outlet neck 42 of the blower housing. Above and in line with such outlet neck, the fitting 43 is provided with a pair of nipples 44 adapted for connection to flexible conduits through which air may pass from the fitting 43 to defroster nozzles (not shown) appropriately mounted adjacent the windshield. The fitting 43 extends rearwardly well beyond the outlet neck 42, where it is provided in its outer end with an air-discharge opening 45. A flap valve 46 pivotally mounted within the casing 43 adjacent the rear of the nipples 44 can be adjusted to direct air discharged from the blower end to the nipples 44 for transmission to defroster nozzles or to the outlet 45 for discharge directly into the automobile-body. The illustrated flap-valve control, comprising a longitudinally movable bar 47 slidably received in an opening in an ear 48 on the valve 46 constitutes the subject matter of my co-pending application Serial No. 103,653, filed July 8, 1949. Desirably, the upper wall of the fitting 43 projects outwardly above the outlet 45 and is bent downwardly to form a deflector 49.

For the purpose of mounting the heater on the dash of an automobile, the rear wall 12 is provided with openings adapted to receive mounting bolts 50. The rear wall 12 is provided in addition with openings for the reception of tubes 51 through which the core 13 is adapted to be connected into the cooling system of the automobile engine in known manner.

When the heater is mounted on the automobile-dash and the core 13 connected through the tubes 51 to the cooling system of the automobile engine so that hot coolant will circulate through the core, rotation of the impellers 25 and 31 by the motor 22 will cause air to be drawn into the casing through the heated core 13. Above the core, such air divides, a portion flowing rearwardly through the partition 18 to be acted upon by the impeller 25 and another portion flowing forwardly to enter the blower-housing 32. As the impeller 25 is presented edgewise to the core 13 and confronts the rear wall 12 of the heater casing, the air upon which it acts is largely delivered radially and tangentially rather than axially, even if the impeller is of the fan-type. In any event, the only escape for air acted upon by the impeller 25 is through the openings 26 which lie largely in the plane of the fan. Because of the spiral shape of the blower housing 32 the axis of the impeller 25 is located nearer one side wall 10 of the casing than the other. As shown in Fig. 3, the impeller 25 is closer to the right-hand side wall 10 than to the left-hand side wall. The location of the blower-outlet 42 determines the direction in which the impellers 25 and 31 rotate, that direction being such that the tips of the blades of the impeller 25 move downwardly adjacent the openings 26 in that side wall of the casing to which the impeller 25 is nearest. As the air delivered from the impeller blades has a substantial tangential component or velocity, this arrangement facilitates the discharge of air past the downwardly and outwardly inclined louvres 27.

At the opposite side of the heater, the upward movement of the blades of the impeller 25 creates a general upward flow of air; and as a result, the air delivered from the impeller 25 at that side of the casing must undergo a substantial reversal in direction of flow in order to permit it to escape between the outwardly and downwardly inclined louvres 27. To aid in this re-

versal of air flow and thus to increase the discharge of air from that side of the casing, a curved deflector 55 may be secured to the back wall 12 of the casing, such deflector extending forwardly to or adjacent the partition 18.

That portion of the heated air which is not drawn rearwardly by the impeller 25 enters the blower housing 32, is acted upon by the impeller 31 therein, and is discharged through the outlet 42 into the fitting 43. Depending upon the position of the valve 46, such air is either conducted to the defroster nozzles or discharged directly into the automobile body through the outlet 45.

I claim as my invention:

1. In an automobile-body heater, a casing having a back wall, side walls, and an open bottom providing an air inlet, a partition disposed within the casing generally parallel to the back wall and having an air-passing opening, a heat-exchanging core positioned within the open casing-bottom and adapted to be connected into an engine-cooling system to heat air entering the casing, at least a portion of the lower edge of said partition being spaced above said core, a baffle extending between the lower portion of said partition and the back wall and co-operating with the partition, the back wall, and side walls to define a fan chamber, a motor mounted within the casing in advance of the partition and having a motor shaft which projects both forwardly and rearwardly from the motor, a fan mounted on the rear end of said shaft within said fan chamber in position to confront said back wall, the side walls of the casing being provided with outlet openings in the plane of the fan between the back wall and the partition, and a blower including a rotary impeller mounted on the front end of the motor shaft for supplying windshield-defrosting air, said fan and blower being arranged so that both serve to draw air upwardly through said core when the motor operates, said fan being located closely adjacent said partition, the air-passing opening in the partition being concentric with the fan and of smaller diameter than the fan, and said fan chamber being free from obstructions interfering with the substantially free flow of air radially from the fan to the outlet openings.

2. The invention set forth in claim 1 with the addition that said baffle has an arcuate center portion concentric with and closely spaced from said fan and downwardly and outwardly sloping end portions meeting said side walls at points below the lowermost outlet openings therein.
